COOLING APPARATUS

Original Filed Feb. 8, 1922

George E. Hulse INVENTOR
BY Robert S. Blair

ATTORNEY

UNITED STATES PATENT OFFICE.

GEORGE E. HULSE, OF NEW HAVEN, CONNECTICUT, ASSIGNOR TO THE SAFETY CAR HEATING & LIGHTING COMPANY, A CORPORATION OF NEW JERSEY.

COOLING APPARATUS.

Original application filed February 8, 1922, Serial No. 534,878. Divided and this application filed December 4, 1924. Serial No. 753,924.

This invention relates to cooling or refrigerating apparatus.

One of the objects of this invention is to provide a refrigerating unit of compact mechanical arrangement and construction, capable of convenient and rapid assembly, thus to lend itself to rapid and inexpensive manufacture, and of thoroughly reliable and dependable action when in use. Another object is to provide a compressor-condenser-receiver unit for a refrigerating apparatus, together with a motor drive for the compressor of simple yet thoroughly practical construction, compact arrangement, and capable of rapid assembly and convenient adjustment when in use. Another object is to provide a practical arrangement for mounting and correlating the several elements of apparatus of the above-mentioned type so as to provide a substantially unitary and self-contained structure. Other objects will be in part obvious or in part pointed out hereinafter.

This application is a division of my application, Serial No. 534,878, filed February 8, 1922.

The invention accordingly consists in the features of construction, combination of elements and arrangement of parts which will be exemplified in the structure hereinafter described and the scope of the application of which will be indicated in the following claims.

In the accompanying drawing, the single figure is a vertical central sectional view of the apparatus in assembled relation, certain related parts being, for simplicity and greater clarity, shown diagrammatically.

Referring now to the drawing, there is shown at 10 the main frame or field frame of an electric motor, the lower end being provided with suitable outwardly directed lugs 11 adapted to form a standard or base for supporting the motor frame 10 in a vertical position. A suitable number of lugs 11 are provided to form a rigid support or base and suitable openings are provided in the lower end of the frame and intervening the lugs 11 for a purpose to be hereinafter more clearly set forth. The field frame 10 is provided with a lower or end piece 12 preferably integrally formed therewith and terminating in a housing 13 in which is adapted to be received the outer race 14 of

a combined radial and thrust ball bearing 55 whose inner race 15 is suitably mounted and secured to the lower end of the armature shaft 16 of the motor, thereby forming a support for one end of the rotatable part of the motor. The housing 13 is interiorly 60 threaded to receive the exteriorly threaded cap 17 whose inner end is adapted to engage and support the outer ball race 14 which, as will be clear from the foregoing, fits snugly within the cylindrical housing 13. The ball race 14 and with it the entire ball bearing and the armature shaft 16 may thus be not only readily assembled but also readily and conveniently adjusted in an axial direction by means of the threaded cap 17 65 whose position within the housing 13 may be fixed after adjustment by means of suitable screws 18 threaded into the end of the housing 13 and extending through suitable serrations in the outer periphery of the flanged 70 portion of the cap 17.

Turning now to the support for the other end of the armature shaft 16 it will be noted that the field frame 10 of the motor is provided with a plurality of upwardly and outwardly extending arms 19 terminating in the ring portion 20 whose upper and interior faces may be machined concentrically with the interior cylindrical surface of the end housing 13 hereinbefore described. The ring portion 20 supported by and preferably formed integrally with the vertical arms 19 is adapted to support a spider having a ring portion 21 machined to fit the surfaces of the ring 20. Screws 20^a may be employed 80 to secure these parts together. The spider is provided with a plurality of arms, two of which are shown in section at 22 and 23 and terminate in a centrally positioned and substantially cylindrical housing 24 in the lower 85 end of which is mounted a ball bearing indicated generally at 25, the outer race 26 fitting within the lower interior of the housing 24. The interior race 27 of the ball bearing 25 is fitted upon a sleeve 28 which 90 is downwardly extended so as to receive within its lower end the upper end 16^a of the armature shaft 16. The latter is rigidly connected with the sleeve 28 so as to form a driving connection by means of the pin 29 95 passing through the lower end of the sleeve 28. The upper end of the armature shaft 16 is thus rigidly supported and it will be 100 105

- 22
- 5 noted that upon adjustment in an axial direction of the armature shaft by means of the threaded cap 17 hereinbefore described the sleeve 28 with its associated ball bearing 25 may partake of a like movement, the housing 24 being suitably machined at its lower interior end as at 30 to permit of a movement in an axial direction of the upper supporting ball bearing 25.
- 10 The sleeve 28 is flanged at its upper end as at 31 so as to fix the position of the inner race 27 of the ball bearing and the latter is held in such position by the hub 32 of a fan indicated generally at 33, the hub 32 being threaded upon the sleeve and against the inner ball race 27 to securely lock the latter in position. A nut 34 is provided for locking the hub 32 of the fan 33 in position upon the sleeve 28. It will be noted that the construction above described thus permits of a convenient and ready assembly of the several parts.
- 15 It may at this point be noted that the fan 33, being thus rigidly mounted upon the shaft 16 of the motor and being driven thereby, is effective to draw air downwardly between the arms 22 and 23 of the supporting spider for a purpose to be more clearly set forth hereinafter and thereupon discharges the air outwardly between the supporting arms 19 and downwardly through the effective or operative portions of the motor. The armature indicated generally at 35 and its associated field windings indicated generally at 36 are thus provided with an effective cooling current of air, which may thereupon exit through the lower end of the field frame 10 and through the spaces intervening the supporting lugs or standards 11. A cover plate 37 provided with an opening through which the motor shaft 16 may pass is mounted as by screws 38 upon the interior end of the housing 13 whereby, together with the adjusting cap 17, the ball bearing supporting the lower end of the shaft 16 is substantially entirely encased and thus protected from dust and foreign matter which may be directed thereto by the current of air or otherwise.
- 20 The motor may be supplied with current from any suitable source, as for example a storage battery 39, and the circuit of the motor comprising the conductors 40 and 41 and hence the operation thereof is preferably controlled by means hereinafter to be more clearly described.
- 25 Taking up now in detail the cooling apparatus there is shown and generally indicated at 42 a compressor preferably of the rotary type mounted upon the flanged portion 43 and preferably integral with an upwardly directed extension 44 of the housing 24 hereinbefore described. The compressor 42 is preferably built up upon the flanged end 43 of the housing 44 and may comprise

for example the substantially cylindrical wall portion 45 and an end or closing plate 46 secured together as by means of the bolts 47. The end plate 46 has an upwardly directed cylindrical extension 48 into the lower end of which the outer race 49 of a ball bearing generally indicated at 50 is adapted to be fitted. The inner race 51 is secured in any suitable manner to the upper end of the shaft 52 of the compressor. A cap 53 is threaded on to the cylindrical extension 48 of the end plate 46 and is adapted to close the bearing housing formed by the extension 48. The several parts forming the casing for the compressor 42 may be accurately machined so that when fitted upon the flanged portion 43 of the housing 44 supported by the spider arms 22 and 23 and placed in assembled relation as shown in the drawing, the upper ball bearing 42 will be in axial alignment with the lower ball bearing 25 which, as hereinbefore described, is by the construction employed also in alignment with the lowermost ball bearing 14—15.

30 The compressor shaft 52 is extended downwardly and is in driving connection with the motor shaft 16 as follows. In the upper end of the sleeve 28 there is pivotally supported a block 54 of a substantially rectangular cross-section, the block 54 being held in position by means of the pin 55 passing through it and through the sleeve 28. The lower end of the compressor shaft 52 is milled out as at 56 to provide an axially extending slot in the lower end thereof into which the block 54 may be received. The milled portion or slot 56 is, moreover, of sufficient extent so as to permit of a relative movement or sliding action to take place between the lower forked end of the shaft 52 and the sleeve 28 within which the lower end of the shaft 52 is received. The milled or slotted portion 56 of the shaft thus not only insures a positive driving connection between the compressor shaft 52 and the motor shaft 16 but also permits of an axial adjustment of the motor shaft 16 by means of the cap 17 hereinbefore described to take place without affecting the compressor shaft 52 and its upper mounting. Furthermore, it may also be noted that the lower or forked end of the shaft 52 which straddles the block 54 preferably fits snugly within the sleeve 28 so that the lower end of the compressor shaft 52 is supported thereby and so that the ball bearing 25, supporting the upper end of the motor shaft 16 also forms the roller bearing for the compressor shaft 52.

35 The compressor 42 on being operated is adapted to compress, as will be more clearly set forth hereinafter, a volatile and condensable gas, such for example as sulphur dioxide, and in order to provide for ade-

quate lubrication of the moving parts of the compressor a suitable lubricant having a different specific gravity from that of the sulphur dioxide is used and may, for example, take the form of a suitable petroleum oil. In order to prevent the leakage of the liquefied gas and lubricant downwardly and into the motor and its operative parts there is associated with the compressor and its driving shaft a suitable seal. This seal comprises in part a bushing 57 having suitably secured to its interior a corrugated expansible tube 58. The bushing 57 is adapted to be threaded into the housing 44 and the threaded connection indicated at 59 is made tight by means of a suitable packing or washer 60 interposed between the flanged end of the bushing 57 and a suitable shoulder on the interior of the housing 44. The interior diameter of the expansible tube 58 is materially greater than the diameter of the shaft 52 and is adapted to encase the latter, as is clearly shown in Fig. 1 of the drawings. At the lower end of the expansible tube 58 there is rigidly secured thereto a collar 61 shaped to form a housing for a second collar 62, which latter is preferably formed of a material of good wearing qualities such as steel for example and whose interior diameter is such as to permit the shaft 52 to rotate therein. The lower end face of the collar 62 indicated at 63 is accurately machined or surfaced to form a close fit with the upper end face of the sleeve 28 which preferably is also made of a material of good wearing qualities such as steel for example. The lower end face 63 of the collar 62 which, as above noted, is fixed against rotation by its engagement with the collar 61 is held in tight contact with the upper end face of the sleeve 28 by reason of the tendency of the corrugated tube 58 to expand thus preventing any leakage which may take place between the shaft 52 and the collar 62 from escaping to the exterior. Furthermore, sufficient liquid including lubricant will be supplied to the relatively moving end faces of the seal-forming collar 62 and sleeve 28 to effectively lubricate these surfaces against excessive wear. Any leakage that finds its way downwardly into the sleeve 28 is prevented from reaching the exterior or the moving parts of the apparatus by means of a diaphragm indicated at 64 in the interior of the sleeve 28 and interposed between the ends of the compressor shaft 52 and of the motor shaft 16. The diaphragm or seal 64 may be made of any suitable material such as, for example, lead or copper, and may be expanded by hammering for example into proper sealing position, a suitable circumferentially extending groove indicated at 65 being provided on the interior of the sleeve 28.

The tightness of the seal formed by the collar 62 and the end face of the sleeve 28 may be adjusted by adjusting the position of the motor shaft 16 and hence of the end face of the sleeve 28 in an axial direction by means of the adjusting cap 17 hereinbefore described.

The compressor 42 discharges the gas under relatively high pressure through the tube 66 from which it passes throughout an inner coil 67 and an outer coil 68 of a condenser. A series of copper sheets, indicated generally at 22^a and spaced from one another in a preferably radial manner, are fitted about the coils 67 and 68 and serve as cooling flanges for bringing about a more effective cooling of the fluid passing through the coils. The condenser coils and their associated cooling flanges form a substantially compact and annularly shaped condenser 85 which preferably surrounds the compressor and is suitably supported upon the arms 22 and 23 of the supporting spider hereinbefore described. The fan 33 whose action has been hereinbefore briefly described is effective to draw a current of air downwardly through the condenser and over the cooling flanges, thus making more effective the action of the condenser in condensing the compressed gas into liquid form. The liquefied gas 95 passes from the condenser through the connecting tube 69 to an annular receiver 70 surrounding the condenser coils 67 and 68 and suitably supported upon the ring portion 21 of the supporting spider. The receiver 70 in being thus positioned is also affected by a current of air drawn through the condenser which it surrounds and the cooling is thus made highly effective.

In the receiver 70 the liquid is permitted to accumulate and since, as above noted, the compressor is supplied with a suitable lubricant, a material quantity of the lubricant will pass off with the gas and will, with the latter, accumulate in the receiver 70. The lubricant and the condensed gas, however, are of different specific gravities and hence a separation may take place within the receiver 70. Adjacent the connecting tube 69, there is positioned in the receiver 70 a baffle plate 71, extending laterally between the two annular walls of the receiver 70 and, as will also be clearly seen from the drawing, contacting with the tube and bottom of the receiver 70.

The mixture of lubricant and liquefied gas, entering the receiver 70 through the tube 69 is because of the baffle plate 71, made to flow completely around the annular path provided by the receiver 70 and before either lubricant or condensed gas may be withdrawn from the receiver 70, the mixture is made to traverse the entire length of the annular path. On the other side of the baffle plate 71 there extends into the receiver 130

70 a tube or conduit 75, the latter being extended downwardly into the receiver 70 to a point adjacent the bottom of the receiver itself. In the course of the travel of the lubricant and condensed gase throughout the annular path in the receiver 70, the lubricant and liquefied gas are permitted to separate, the liquefied gas, such as sulphur dioxide being of greater specific gravity than the lubricant or oil, separates into a lower stratum, and the lubricant separates into an upper stratum. These two strata become well defined by the time the two liquids have traversed the length of the annular path in the receiver 70 and the liquids of the respective strata may thereupon be individually withdrawn. The tube 75 extends into the lower stratum of sulphur dioxide and the latter may thus be individually withdrawn; a tube 74 is extended into the receiver 70 adjacent the baffle plate 71 and its opening is at such a height within the receiver 70 that only oil or lubricant from the upper stratum can be withdrawn therefrom. The tube or conduit 74 enters a cap 53 at the upper end of the compressor housing, so that the lubricant withdrawn through the tube 74 is supplied to the moving parts of the compressor. An orifice member 74^a detachably mounted in the cap 53 serves to limit the flow of lubricant to the desired extent.

As conducive to a clearer understanding of certain features of this invention, it might be pointed out that the liquefied gas, withdrawn through the tube 75 from the receiver 70, may be passed through a suitable expansion device 76 (diagrammatically indicated), the reduction in pressure thus produced permitting the liquefied gas to evaporate and resulting in a material reduction in temperature. From the expansion device the expanded gas may be passed through a suitable heat exchange apparatus diagrammatically indicated at 77 and conveniently taking the form of a coil of tubing; to the latter, the substance to be reduced in temperature may be thermally related in any suitable manner so that heat may be extracted therefrom. From the heat exchange device or coil of tubing 77, the gas may be returned to the intake side of the compressor as by way of the tube or conduit 79. The expansion device and the heat exchange apparatus may be conveniently embodied in the forms disclosed in my above-mentioned co-pending and parent application. The circuit 40-41 of the motor 35 may be controlled in any convenient manner, but is preferably automatically controlled as disclosed in my above-mentioned parent application.

It will thus be seen that there has been provided in this invention an apparatus in which the several objects hereinbefore set forth, as well as others, are attained and in

which many advantages are successfully achieved. It will be noted that there has been provided an apparatus in which the several parts may be rapidly and accurately assembled for operation and that when so assembled a compact, unitary and substantially self-contained refrigerating unit is provided. Moreover, it will be noted that the parts are of rugged and durable construction and are thus well adapted to meet the conditions of hard practical use. It will also be seen that the several parts of the apparatus may be conveniently and rapidly adjusted for most effective mechanical operation, and that, on the whole there has been provided an apparatus of exceedingly practical construction, conducive not only to rapid and inexpensive manufacture, but also to durability and dependability when in use.

As many possible embodiments may be made of the above invention and as many changes might be made in the embodiment above set forth, it is to be understood that all matter hereinbefore set forth is to be interpreted as illustrative and not in a limiting sense.

I claim as my invention:

1. In apparatus of the nature of that herein described, in combination, a main frame, a prime mover having a shaft rotatably supported therein, an auxiliary frame, a compressor having a substantially fluid-tight casing mounted upon said auxiliary frame and having an operative shaft extending through said casing, a detachable driving connection between said two shafts, means for mounting said auxiliary frame upon said main frame thereby to aline said two shafts in operative connection, a detachable fluid-tight connection between said shafts and said compressor casing comprising an expansible sleeve surrounding said compressor shaft and rigidly secured at one end to said casing to be movable therewith and with said auxiliary frame, a collar upon said prime mover shaft, means having a bearing surface mounted upon the other end of said expansible sleeve and adapted to contact with said collar to form therewith a fluid-tight joint, and means for moving said prime mover shaft in an axial direction thereby to adjust the pressure of contact between the bearing surface on said expansible sleeve and said collar on said prime mover shaft.

2. In apparatus of the nature of that herein described, in combination, a main frame, a prime mover having a shaft rotatably supported therein, an auxiliary frame, a compressor having a substantially fluid-tight casing mounted upon said auxiliary frame and having an operative shaft extending through said casing, a detachable driving connection between said two shafts,

- means for mounting said auxiliary frame upon said main frame thereby to aline said two shafts in operative connection, a detachable fluid-tight connection between said shafts and said compressor casing comprising an expansible sleeve surrounding said compressor shaft and rigidly secured at one end to said casing to be movable therewith and with said auxiliary frame, a collar upon said prime mover shaft, and means having a bearing surface mounted upon the other end of said expansible sleeve and adapted to contact with said collar to form therewith a fluid tight joint. 5 70
- 10 3. In apparatus of the nature of that herein described, in combination, a prime mover having an operative shaft, a compressor having a substantially fluid-tight casing into which said shaft extends, a collar mounted upon said shaft intermediate said prime mover and said compressor casing, an expansible sleeve surrounding said shaft and interposed between said casing and said collar and in fluid-tight connection at one end 20 75 with said casing, means having a bearing surface mounted at the other end of said expansible sleeve adapted to engage said collar and form therewith a fluid-tight connection, and means for varying the expansive force of said expansible sleeve. 80
- 25 4. In apparatus of the nature of that herein described, in combination, a prime mover having an operative shaft, a compressor having a substantially fluid-tight casing into 30 85 which said shaft extends, a collar mounted upon said shaft intermediate said prime mover and said compressor casing, an expansible sleeve surrounding said shaft and interposed between said casing and said collar and in fluid-tight connection at one end with said casing, and means having a bearing surface mounted at the other end of said expansible sleeve adapted to engage said collar and form therewith a fluid-tight 35 90 connection. 95
- 40 5. In apparatus of the nature of that herein described, in combination, a main frame, a prime mover having an operative shaft rotatably supported within said main frame, said shaft having a collar rigidly mounted thereon substantially exteriorly of said main frame, a compressor having a substantially fluid-tight casing and an operative shaft therefor extending through said casing, 45 100 means for mounting said compressor in relation to said main frame thereby to aline the shaft of said prime mover with the shaft of said compressor, a slid able driving connection between said two shafts, an expansible sleeve rigidly connected at one end thereof with said compressor casing and surrounding said compressor shaft, said sleeve being interposed between said casing and said collar, means having a bearing 50 105 surface associated with said sleeve and at the other end thereof adapted to contact with said collar thereby to form a fluid-tight connection, and means for moving the shaft of said prime mover longitudinally thereby to adjust the pressure of contact between said bearing surface and said collar. 55 110
- 60 6. In apparatus of the nature of that herein described, in combination, a main frame provided with a bearing at one end thereof, a prime mover mounted within said frame and having one end of the operative shaft thereof rotatably supported in said end bearing, a ball bearing having its inner race rigidly mounted upon the other end of the shaft of said prime mover, an auxiliary frame detachably secured to the other end of said main frame and provided and supporting the outer race of said ball bearing thereby to aline said ball bearing with said first-mentioned bearing, a compressor 65 115 mounted upon said auxiliary frame and having an operative shaft, means forming a detachable driving connection between the adjacent ends of the shaft of said prime mover and of said compressor, and means for adjusting said prime mover shaft with said ball bearing in a direction axially of said shaft. 70 120
- 65 7. In apparatus of the nature of that herein described, in combination, a main frame provided with a bearing at one end thereof, a prime mover having an operative shaft one end of which is rotatably supported in said end bearing, a bearing for the other end of the shaft of said prime mover, a detachable auxiliary frame secured to the other end of said main frame and adapted to support said second mentioned bearing in alinement with said end bearing, a compressor mounted upon said auxiliary frame and having a bearing in substantial alinement with said above-mentioned bearings for supporting one end of the operative shaft of said compressor, and means forming a detachable and alining connection between the adjacent ends of the shafts of said prime mover and said compressor whereby said adjacent end of said compressor shaft is rotatably supported substantially by said second-mentioned bearing. 75 125
- 70 8. In apparatus of the nature of that herein described, in combination, a main frame provided with a bearing at one end thereof, a prime mover having an operative shaft one end of which is rotatably supported in said end bearing, a bearing for the other end of the shaft of said prime mover, a detachable auxiliary frame secured to the other end of said main frame and adapted to support said second-mentioned bearing in alinement with said end bearing, a compressor mounted upon said auxiliary frame and having an operative shaft rotatably supported substantially in alinement with said two bearings supporting the shaft of 80 130

- 5 said prime mover, and a slidale driving connection between the adjacent ends of the shafts of said prime mover and said compressor adapted to place said shafts in driving connection when said auxiliary frame is attached to said main frame and to disengage said driving connection when said auxiliary frame is detached from said main frame.
- 10 9. In apparatus of the nature of that herein described, in combination, a main frame provided with a bearing at one end thereof, a prime mover mounted within said frame and having one end of its operative shaft rotatably supported in said end bearing, an auxiliary frame provided with a bearing for supporting the other end of the shaft of said prime mover and provided with a bearing oppositely disposed from 15 and in alinement with said second-mentioned bearing, means for securing said auxiliary frame to the other end of said main frame and adapted to aline said second-mentioned bearing with said end bearing thereby to rotatably support the shaft 20 of said prime mover, a compressor mounted in said auxiliary frame and having one end of its operative shaft rotatably supported in said third-mentioned bearing, and a driving and alining connection between the other end of the shaft of said compressor and the shaft of said prime mover adapted to permit relative axial movement between 25 said two shafts.
- 30 10. In apparatus of the nature of that herein described, in combination, a main frame provided with a bearing at one end thereof, a prime mover mounted within said frame and having one end of the shaft thereof rotatably supported in said end bearing, an auxiliary frame having a pair of alined bearings, a compressor mounted within said auxiliary frame and having its operative shaft rotatably supported within 35 said two alined bearings, means for securing said auxiliary frame to the other end of said main frame and adapted to aline one of said bearings therein with said end bearing, and means forming a driving connection between the other end of the shaft 40 of said prime mover and the shaft of said compressor.
- 45 11. In apparatus of the nature of that herein described, in combination, a motor frame having a bearing at one end thereof, a driving shaft having an armature mounted thereon within said motor frame and having one end of said shaft supported in said bearing, a compressor having an operating shaft therefor, means mounting said compressor at the other end of said motor frame and with said two shafts in axial alinement, a bearing for the compressor shaft at the end thereof remote from said motor frame, means forming a driving connection 50 between said two shafts, and means adjacent said driving connection forming an intermediate bearing for both of said shafts.
- 55 12. In apparatus of the nature of that herein described, in combination, a motor frame carrying therein an armature and a driving shaft, said frame being arranged to support said driving shaft in an upright position, means at the lower end of said motor frame forming a bearing for the lower end of said driving shaft, an auxiliary frame detachably secured to the upper end of said motor frame and provided with bearing means for rotatably supporting the upper 60 end of said driving shaft, a compressor mounted upon said auxiliary frame and having an operative shaft extending in substantial alinement with said driving shaft, and means forming a detachable connection between the adjacent ends of said two shafts.
- 65 13. In apparatus of the nature of that herein described, in combination, a motor frame having therein an upright driving shaft with an armature thereon, bearing means at the lower end of said motor frame for supporting the lower end of said driving shaft, the upper end of said driving shaft being recessed, a ball bearing having its inner race mounted upon the upper end 70 of said driving shaft, an auxiliary frame adapted to be detachably secured to the upper end of said motor frame, said auxiliary frame having substantially centrally disposed means for engaging the outer race of said ball bearing, and a compressor mounted upon said auxiliary frame and having an operative shaft extending in substantial alinement with said driving shaft, the lower end of said compressor shaft being received within the recess of said driving shaft, thereby to be rotatably supported by said ball bearing.
- 75 14. In apparatus of the nature of that herein described, in combination, a main frame provided with a bearing at one end thereof, a prime mover mounted within said frame and having one end of the shaft thereof rotatably supported in said end bearing, an auxiliary frame member mounted upon the other end of said main frame and supporting bearing means thereon substantially alined with said end bearing, a sleeve member mounted in said bearing means, a compressor mounted upon said auxiliary frame member and having an operative shaft in substantial alinement with said prime mover shaft, and means for rotatably supporting said compressor shaft at the end thereof remote from said main frame, the adjacent ends of said two shafts extending into said sleeve member.
- 80 15. In apparatus of the nature of that herein described, in combination, a main frame provided with a bearing at one end 85

- thereof, a prime mover mounted within said frame and having one end of the shaft thereof rotatably supported in said end bearing, an auxiliary frame member mounted upon 60
5 the other end of said main frame, a compressor supported by said auxiliary frame member and having its shaft extending toward the shaft of said prime mover, a sleeve member for receiving the adjacent ends of 65
10 said two shafts, a ball bearing having its inner race supported by said sleeve, and means on said auxiliary frame for supporting the outer race of said ball bearing.
16. In apparatus of the nature of that 70
15 herein described, in combination, a motor frame having a bearing at one end thereof, a driving shaft having an armature mounted thereon within said motor frame and having one end of said shaft supported in 75
20 said bearing, a compressor having a supporting shaft therefor, means detachably mounting said compressor at the other end of said motor frame and with said two shafts in axial alinement, said means carrying bearing means for one of said shafts, and a driving coupling between the adjacent 80
25 ends of said two shafts arranged to effect or disrupt the driving connection therebetween upon said compressor mounting means
30 being attached to or detached from said motor frame.
17. In apparatus of the nature of that 85
herein described, in combination, a frame carrying a prime mover having an operating 90
35 shaft, a compressor having a casing through which extends the shaft of the compressor, means for securing said compressor to said frame and arranged to substantially aline the adjacent ends of said two shafts, said
40 prime mover shaft having a recess in the end thereof and adapted to receive therein the compressor shaft, and means in fluid tight connection with said compressor casing and adapted, upon said compressor being secured to said frame, to be seated 95
45 against the end of said prime mover shaft and form a seal therewith.
18. In apparatus of the nature of that 100
herein described, in combination, a main 105
50 frame provided with a bearing at one end thereof and having at the other end supporting means concentric with said bearing; a prime mover mounted in said frame and having one end of the shaft thereof rotatably supported in said end bearing, a compressor having a casing provided with a
55 bezelled portion adapted to inter-fit with said concentric supporting means and having an operating shaft centrally supported with respect thereto, said two shafts being thereby alined and means forming a common bearing for the adjacent ends of 60
said two shafts.
19. In apparatus of the nature of that 65
herein described, in combination, a main 70
frame provided with a bearing at one end thereof and having at the other end supporting means concentric with said bearing, a prime mover mounted in said frame and having one end of the shaft thereof rotatably supported in said end bearing, a compressor having a casing provided with a bezelled portion adapted to inter-fit with said concentric supporting means and having an operating shaft centrally supported 75
with respect thereto, said two shafts being thereby alined, and means forming a driving coupling between the adjacent ends of said two shafts and arranged to complete the driving connection therebetween upon 80
said compressor casing being assembled to said main frame.
20. In apparatus of the nature of that 85
herein described, in combination, a prime 90
mover and a compressor, each having a shaft, means supporting said prime mover and said compressor with their shafts in axial alinement, means forming a driving connection between the adjacent ends of said shafts, and means forming a fluid tight seal 95
between the casing of the compressor and the shaft of the prime mover.
21. In apparatus of the nature of that 100
herein described, in combination, a prime 105
mover and a compressor, each having a shaft, means supporting said prime mover and said compressor with their shafts in axial alinement, means forming a driving connection between the adjacent ends of said shaft, means forming a fluid tight seal between the casing of the compressor and the shaft of the prime mover and dependent in its effectiveness upon the axial position of said prime mover shaft relative to the casing of the compressor, and means for adjustably moving said prime mover shaft in an axial direction and relative to the casing of the compressor.
- In testimony whereof, I have signed my name to this specification, this 21st day of November, 1924 110
- GEORGE E. HULSE.
